[57] CLAIM

The ornamental design for a combined calendar, memo and pencil holder, substantially as shown and described.

DESCRIPTION

FIG. 1 is a top perspective view of a combined calendar, memo and pencil holder showing our new design in a horizontal orientation;

FIG. 2 is a front perspective view thereof shown in vertical orientation;

FIG. 3 is a top plan view thereof;

FIG. 4 is a bottom plan view thereof;

FIG. 5 is a right side elevational view thereof;

FIG. 6 is a front elevational view thereof; and

FIG. 7 is a rear elevational view thereof.

The side not shown is a mirror image of the view shown in FIG. 5.
